United States Patent Office.

MAURICE LANGHORNE, OF WASHINGTON, DISTRICT OF COLUMBIA.

Letters Patent No. 99,919, dated February 15, 1870.

IMPROVEMENT IN LOCK-NUT.

The Schedule referred to in these Letters Patent and making part of the same.

To all whom it may concern:

Be it known that I, MAURICE LANGHORNE, of the city and county of Washington, in the District of Columbia, have invented a new and improved Nut-Lock; and I do hereby declare that the following is a full, clear, and exact description of the same, reference being had to the accompanying drawings, making a part of this specification, in which—

Figure 1 is a side elevation;

Figure 2, a longitudinal section; and

Figure 3 is an end view.

This invention has for its object to prevent the turning back of a nut after it has once been screwed on its bolt as tightly as may be necessary in order to clamp the material through which the bolt passes.

In the drawings—

A is an exteriorly-threaded bolt, having a longitudinal groove, *a*, cut in one side.

B is a washer, whose upper surface is serrated, so as to form a ratchet.

The washer incloses the bolt A, and has a tongue, *b*, fig. 2, which enters the groove *a*, and so prevents the washer from turning on the bolt. Instead of the tongue *b*, the washer may be finished with a straight facet on its inner edge, the bolt A being finished with a corresponding facet.

C is a nut, screwed upon the bolt A and provided with a spring-pawl, *c*, fig. 1, the same consisting, in

this instance, of a wire in the shape of an inverted U, whose legs pass through orifices in the nut, one end being upset flush with the lower face of the nut, and the other end projecting below the said lower face. Hence, when the nut and washer are forced into close contact, by screwing the former upon the bolt and clamping the latter between the nut and the material through which the bolt passes, the projecting end of the pawl *c* rubs over the ratchet, and, while the latter presents no obstacle to screwing the nut on, it prevents the nut from turning backward accidentally.

Having thus described my invention,

What I claim as new, and desire to secure by Letters Patent, is—

1. The combination of a ratchet-washer with a screw-threaded nut provided with a spring-detent, substantially as and for the purpose specified.

2. The combination of a ratchet-washer with a screw-threaded nut provided with a spring-detent and with a screw-threaded bolt or axle, substantially as and for the object set forth.

To the above specification of my invention I have signed my hand this 18th day of January, 1870.

M. LANGHORNE.
